UNITED STATES PATENT OFFICE

2,555,462

WHIPSTOCK

Julius S. Beck, Los Angeles, Calif.

Application November 3, 1947, Serial No. 783,784

6 Claims. (Cl. 255—1.6)

1

This invention relates to oil well drilling tools, and more particularly to what is known in the art as a whip-stock.

The chief detriments of an ordinary whip-stock in an oil well are caused by the use of cement. Cement, besides constituting a great expense, offers no reasonable degree of success, due to its lack of adhesion to steel. Under drilling operations the constant rotary contact of the bit cutters against the body of the whip-stock results in the whip-stock being turned from its fixed position and/or slipping into the new hole. Furthermore, the cement-contaminated mud necessitates the expense of cleaning the hole and the price of new mud.

The general object of my invention is to provide a whip-stock which will overcome the disadvantages above stated.

A more particular object is to provide a whip-stock which may be set and fixed without cement in a well hole for directing the drill in any desired direction.

Another object is to provide a whip-stock by means of which a wall sample of the formation through which the well is drilled may be obtained, while the whip-stock is being set in the well.

A further object is to provide a whip-stock which may be operated in a well casing to cut a sliver or a window in the casing through which the drilling tools may penetrate into the open formation past a broken tool in the casing below.

A further object is to provide a whip-stock by means of which dogs may be driven therefrom into the well formation to prevent the whip-stock from turning and/or slipping in the well into a new hole leading from the well.

Other objects and advantages will appear hereinafter as this specification progresses.

The invention is illustrated in the annexed drawings, which form a part of this specification and in which

Fig. 1 is a vertical longitudinal section of my invention shown in position in a well casing for driving dogs through the casing into the earth surrounding the casing for preventing the whip-stock from turning and for guiding the cutting tool to cut a sliver or window in the casing through which the drill may be guided to penetrate into the surrounding earth to cut a new hole.

Fig. 2 is a vertical longitudinal section of my invention shown in position with the whip-stock set upon a broken tool in the well casing and the dogs driven through said casing into the sur-

2

rounding earth to prevent the whip-stock from turning, and with the cutting tool being guided to cut a sliver or window in the casing through which the drill may be guided to penetrate the surrounding earth to drill a new hole.

Fig. 3 is a vertical longitudinal section like Fig. 2, showing the whip-stock set upon a broken tool in a well casing and the dogs driven through the casing into the surrounding earth to prevent turning of the whip-stock, and the cutting tool and hammer, and their operating string removed from the casing after a window has been cut through the casing, and showing a drill string extending downwardly in the casing and out through said window into the surrounding earth, in the act of drilling a new hole from the casing above the whip-stock and the broken tool in the lower part of the casing.

Fig. 4 is a horizontal section taken on line 4—4 of Fig. 1.

Fig. 5 is a horizontal section taken on line 5—5 of Fig. 1.

Fig. 6 is a horizontal section taken on line 6—6 of Fig. 1.

Fig. 7 is a horizontal section taken on line 7—7 of Fig. 3.

Fig. 8 is a horizontal section taken on line 8—8 of Fig. 3.

Fig. 9 is an enlarged longitudinal section of my invention.

Fig. 10 is an enlarged elevation of my invention viewed at right angles to Fig. 9.

Fig. 11 is an enlarged longitudinal section of my invention showing the hammer in the act of driving the dogs through the whip-stock.

Fig. 12 is a horizontal section taken on line 12—12 of Fig. 9.

Fig. 13 is a horizontal section taken on line 13—13 of Fig. 9.

Referring more particularly to the drawings, in which corresponding parts are designated by the same reference numerals in all of the figures, my invention includes generally a whip-stock body member 1, a whip-stock sub-member 2, a conventional frangible connection 3 and a frangible connection 4 for connecting said sub-member to said body member, a plurality of earth-engaging dogs 5, an anvil 6 on said sub, and a hammer 7 connected to the lower end of a whip-stock string of tubing 8.

The lower end portion 9 of said whip-stock body member 1 is cylindrical and of such diameter as to slidably fit in a well hole or well casing 10, and from the upper end of said lower end portion 9 at one side thereof the whip-stock

member is inclined upwardly toward its opposite side to its upper end 11, forming an inclined guiding surface 12 which is concaved transversely. The whip-stock body member 1 is provided with a plurality of radial slots 13 extending downwardly and curving outwardly from its inner inclined surface 12 to its opposite outer cylindrical surface 14, through which slots 13 extend said earth-engaging dogs 5.

The whip-stock sub 2 is of cylindrical tubular form of such diameter as to slide within the well casing 10, or within an uncased well hole. The upper end of said sub 2 is closed by a head 15 from which a threaded pin 16 projects upwardly, and said head and pin are provided with a duct 17 extending axially therethrough, for the purpose hereinafter more fully described. The lower portion of one side of the tubular wall 18 of the sub 2 is cut away, as at 19, and the lower end of said wall at the upper end of said cut-away portion is formed with a concaved transverse serrated cutting edge 20, while the other side of said tubular wall 18 opposite said cut-away portion 19, below said cutting edge 20 is inclined inwardly, as at 21 to fit and slidably engage the inner inclined concaved surface 12 of the whip-stock body 1. In said other side of said tubular wall 18 is provided a slot 22 extending longitudinally of the sub 2 to receive the frangible connection 3, and immediately below the lower end of said slot on the inner side of the inclined portion 21 of the tubular sub wall 18 is formed a pocket 23 by means of a narrow wall 24 extending upwardly from the inner side of said inclined wall portion 21 and transversely thereof.

The conventional frangible connection 3 comprises a pair of screws 25 which are threaded in and extend through the upper end of the whip-stock body 1 and the sub wall 18 for holding the whip-stock and the sub together against relative movement until the whip-stock is lowered in a well and is set in the well.

The frangible connection 4 comprises a screw 26 threaded at its outer end in the upper end of the whip-stock body 1 and extending through the slot 21, in the tubular wall 18 of the sub 2, between the screws 25 of the frangible connection 3, there being a head 27 on the inner end of said screw which engages the inner side of the tubular wall 18 at opposite sides of said slot 21 for holding the lower inclined portion 21 of said tubular wall 18 in sliding engagement with the inner inclined surface 12 of the whip-stock body 1.

A threaded box 28 is screwed on the threaded pin 16 on the upper end of the whip-stock sub 2, and the upper end of said box forms the anvil 6. From the upper end of said box extends a connecting plunger shaft 29 which is formed with a head 30 on its upper end, and said box, shaft and head are formed with a duct 31 extending therethrough and communicating at its lower end with the upper end of the pin duct 17. The connecting shaft 29 slidably extends through an axial bore 32 in the hammer 7, which hammer is in the form of a head closing the lower end of a tubular hammer sub 33, the upper end of which sub is threaded at 34 on the lower end of the whip-stock string of tubing 8.

The operation of my invention is as follows:

When a drill bit 35 breaks off a drill string in the bottom of a well, my whip-stock is assembled, as shown in Figs. 9, 10, 12 and 13 of the drawings, and the pin 15 on the upper end of the sub 2 is threaded into the box 28 on the lower end of the

connecting plunger shaft 29 depending from the hammer 7 on the lower end of the whip-stock string 8, with the head 30 on the upper end of said shaft resting upon the upper end of said hammer 7 within the sub 33, thus supporting the whip-stock on the lower end of the whip-stock string 8, as shown in Fig. 1 of the drawings. With the whip-stock assembled as above described the whip-stock body 1 is secured at its upper end in fixed relation to the whip-stock sub 2 by the screws 25 of the frangible connection 3, with the screw 26 of the frangible connection 4 extending through the lower end of the slot 22 in said sub 2. My whip-stock is then lowered in a well by means of the whip-stock string 8 as shown in Fig. 1, until the lower end of the whip-stock body 1 rests upon the broken bit 35 in the bottom of the well and arrests downward movement of the whip-stock in the well, while the string 8 is allowed to continue its downward movement until the hammer 7 strikes the anvil 6 a blow and drives down the sub 2 in the whip-stock body 1, shearing off the inner end portions of the screws 25 and allowing said sub 2 to be driven down by said hammer 7 striking said anvil 6, until the lower end 36 of the lower portion 21 of the tubular wall 18 of the sub 2, striking the upper ends of the dogs 5 drives said dogs down through the slots 13 in the whip-stock body 1 until the lower end portions of said dogs are driven into the earth surrounding the well to hold the whip-stock body 1 against turning in the well by constant rotary contact of the cutters of a drill bit, as shown in Fig. 2 of the drawing, during which downward driving movement of the sub 2 the screw 26 passes upwardly through the sub slot 22 and holds the lower portion 21 of the tubular wall 18 of the sub in sliding contact with the inclined surface 12 of the whip-stock body 1 and lower driving end 36 of said lower portion 21 of said sub wall 18 in engagement with the upper ends of the dogs 5, until said dogs are driven into the earth by said end 36 of said portion of said sub wall, as aforesaid, at which time the upper end of the slot 22 engages and shears off the inner end of the screw 26, which end drops into the pocket 23, and thereby disconnects the sub 2 from the whip-stock body 1. By moving the whip-stock string 8 up and down the hammer 7 may be caused to strike the anvil 6 a series of blows to drive the sub 2 down further, whereby said sub will be guided to one side by its engagement with the inclined surface 12 of the whip-stock body 1, so that the cutting edge 20 of the sub 2 will engage and cut a window 37 in the casting 9 and penetrate the earth and start new hole 38 in the earth at said side of the well above the broken bit 35 in the bottom of the well, as illustrated in Figs. 2 and 3 of the drawings. The string 8 and sub 2 are then lifted out of the well and a drill string 39 is then lowered in the well, and, guided by its engagement with the inclined surface 12 of the whip-stock body 1, enters the new hole 38, started by the sub 2 as aforesaid, to drill the new hole in the earth down past the broken tool 35 in the bottom of the well. In starting the new hole by driving the sub 2 out of the well to one side thereof, as aforesaid, the sub fills up with the earth from the new hole, which earth is carried up by said sub when it is lifted out of the well, and said earth shows the operator of my invention the formation of the earth in which the new hole is to be drilled.

I claim:

1. A whip-stock including a whip-stock body,

a hollow sub open and formed at its lower end with a cutting edge, connecting means for connecting said sub to said whip-stock body, securing means for said whip-stock body, means for driving said sub down, when said whip-stock body is set in a well, for releasing said connecting means from said sub and for operating said securing means to secure said whip-stock body against turning in the well, and means for guiding said sub during its downward movement.

2. A whip-stock including a whip-stock body, dogs slidably fitted in said whip-stock body, a sub formed with a driving end, a frangible connection for slidably connecting said sub to said whip-stock body with the driving end of said sub adjacent the upper inner ends of said dogs, an anvil on said sub, a hammer, a tool string on which said hammer is secured, and means for slidably connecting said sub to said tool string to enable said hammer to strike said anvil and drive down said sub so that its driving end will drive said dogs into the earth surrounding a well, in which the whip-stock body is set, and to shear said frangible connection when said dogs are so driven.

3. A whip-stock as characterized by claim 2 in which the frangible connection comprises a screw threaded in the whip-stock body and extending through a longitudinal slot provided in the wall of said sub, with the head of said screw slidably engaging the inner side of the sub wall, the upper end of said slot being arranged to engage and shear off said screw when the dogs are driven into the earth surrounding the well.

4. A whip-stock as characterized by claim 1 in which the sub is hollow and open at its lower end, and is formed with a cutting edge on its lower end, so that when the sub is driven down by the driving means it will be guided by the whip-stock body, to cause said cutting edge to cut a window in a casing in the well through

which window the sub may pass to penetrate the earth surrounding the well casing and receive a sample of said earth.

5. A whip-stock as disclosed including a whip-stock body, dogs slidably in said body, a sub positioned with its lower end engaging the upper end of said dogs, and means for driving said sub to cause its lower end to drive said dogs into the earth surrounding the well, when the whip-stock body is set in the well.

6. A whip-stock including a whip-stock body, a sub, a pair of screws threaded into said body and said sub for holding said body and said sub in fixed relation to each other, said sub being provided with a longitudinal slot therein, between said pair of screws, a screw extended through said slot and threaded in said body, securing means for said whip-stock body, means for driving down said sub for shearing said pair of screws, and driving said securing means into the earth, in which the well and the whip-stock are located, to cause said securing means to prevent turning of said whip-stock body in the well, until the upper end of said slot strikes said screw, extending through said slot, and shears said screw.
